(57) **CLAIM**

The ornamental design for a fog lamp, as shown and described.

DESCRIPTION

FIG. 1 is a front, right, top perspective view of a fog lamp showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

A second embodiment of the claimed design for the fog lamp is a mirror image of the fog lamp as shown in FIGS. 1 to 6. The broken lines in the drawings indicate a boundary between claimed and unclaimed portions, and form no part of the claimed design. The deemphasized, grayscale portions shown inside the broken line boundary form no part of the claimed design.
